UNITED STATES PATENT OFFICE

136,648

DESIGN FOR A COMBINED BILLFOLD AND SEWING KIT

Jacques Schwalbe, Kew Gardens, N. Y.

Application July 14, 1943, Serial No. 110,665

Term of patent 7 years

To all whom it may concern:

Be it known that I, Jacques Schwalbe, a citizen of Belgium but having declared my intention of becoming a citizen of the United States, residing in Kew Gardens, in the county of Queens, city and State of New York, have invented a new, original, and ornamental Design for a Combined Billfold and Sewing Kit, of which the following is a specification, reference being had to the accompanying drawing, forming a part thereof, in which:

Fig. 1 is a perspective view of a combined billfold and sewing kit embodying my new design, the view showing the article in closed position; and

Fig. 2 is a perspective view of the combined billfold and sewing kit in open position.

I claim:

The ornamental design for a combined billfold and sewing kit, as shown.

JACQUES SCHWALBE.
